UNITED STATES PATENT OFFICE.

JAMES W. BEACH, OF CHICAGO, ILLINOIS, ASSIGNOR TO FREDERICK W. BEACH, OF PAOOLI, NORTH DAKOTA.

SAFETY DEVICE FOR ELEVATORS.

No. 895,146.

Specification of Letters Patent.

Patented Aug. 4, 1908.

Application filed April 5, 1907. Serial No. 366,463.

To all whom it may concern:

Be it known that I, JAMES W. BEACH, a citizen of the United States, residing at Chicago, in the county of Cook and State of Illinois, have invented certain new and useful Improvements in Safety Devices for Elevators, of which the following is a specification.

My invention relates to improvements in safety devices for elevators, and the object 10 of my improvements is to provide means which will prevent passengers and other persons from being killed or injured by the top of the elevator cage and the floor of the building in which said cage is located.

15 In the drawing:—Figure 1 is a top plan view of an elevator cage equipped with my safety device. Fig. 2 is a top plan view of an elevator cage equipped with a safety device of modified construction. Fig. 3 is a cross-20 sectional view taken on the line 3—3 of Fig. 2. Fig. 4 is a cross-sectional view taken on the line 4—4 of Fig. 1. Fig. 5 is a detail perspective of an elevator cage made in accordance with my invention without a lintel over the 25 entrance doorway and indicating the relation of the top opening to said doorway.

Referring to the drawing in detail:—The reference numeral 8 indicates the top of the elevator cage, having secured thereto a cross-30 beam 9, and having in one side of said top an opening 10, preferably of rectangular form, which said opening should be located directly above the entrance doorway S of the elevator cage and should be about the same 35 width as said doorway (or wider) and extending from said doorway well inwardly toward said beam 9, the top opening 10 being a practical continuation of the doorway S. In other words, said entrance doorway of said 40 elevator cage has no permanent fixed lintel or other dangerous obstruction over said entrance doorway.

Arranged to normally guard or close the 45 opening 10 (Fig. 1) is a trap-door 11, pivoted at 12 to the top of the elevator cage and having a counter-weight, which said counter-weight is indicated by 13. Normally, this trap-door when closed engages a stop 14, constituting practically a part of the top 8, 50 and assumes a horizontal position, as shown in Fig. 4. Should the elevator cage descend suddenly while a passenger or other person is in the said entrance doorway, the passenger or person aforesaid, instead of being 55 caught and crushed between the floor of the

building and the top of the elevator cage, will engage the trap-door, which said trap-door will instantly assume a vertical position, as shown by the dotted line 11^a in Fig. 4.

In the modified construction shown in 60 Figs. 2 and 3 the trap-door consists of a number of independent sections, 15, each being heavier at its rear or inner end to provide counterweight. These sections 15 normally 65 assume a horizontal position, as shown in Fig. 3, but will also assume (upon pressure being applied to the outer lower side thereof) a vertical position, as shown by the dotted line 15^a, Fig. 3.

From the foregoing and with reference to 70 the drawings it will be apparent that the pivot 12 is located parallel to and adjacent to the inner edge of the top opening 10 and just below the plane of the elevator cage top 8. The inner end, therefore, of the door 75 mechanism is held in normal position below the lower surface of said top 8 and the outer or free end of said mechanism is prevented from moving below the normal position by contact of said inner end engaging with the 80 under side of the top 8.

It is furthermore to be noted that in its preferred embodiment my door mechanism is so mounted with respect to the axis 12 that normally the free end thereof is just sufficiently heavier than the weighted end as to be carried in position to guard or close the opening 10, but the mass of such mechanism is eccentric to and normally above said axis 12. In other words, the center of gravity of 90 the door mechanism is normally above and outward from the axis, but as soon as the free end of the mechanism is given a slight upward impulse said center of gravity moves inwardly over the axis 12 whereby the mass 95 of the counterbalanced door mechanism causes the same to quickly assume and retain an open position until being reset to the normal horizontal position by the operator of the cage.

Having thus described my invention, what I claim as new, and desire to secure by Letters-Patent is

1. In safety apparatus for elevators, the combination of a cage having a vertical doorway and a top having a horizontal opening in direct unobstructed communication with said doorway, a horizontal axis located below and parallel to the inner edge of the said top opening, and normally horizontal door mech- 110

anism pivoted intermediate its inner and outer ends on said axis, said inner end being adapted to engage beneath the lower surface of the cage top to limit pivotal movement of the mechanism in one direction.

2. In safety apparatus for elevators, the combination of a cage having a vertical doorway and a top having a horizontal opening in direct unobstructed communication with said doorway, a horizontal axis located below and parallel to the inner edge of the said top opening, and normally horizontal door mechanism pivoted intermediate its inner and outer ends on said axis, the mass of the door mechanism being so disposed with relation to the said axis that the center of gravity thereof is normally above and outward of the axis but movable inwardly over the axis upon up-

ward movement of the outer end of the door mechanism.

3. In safety apparatus for elevators, the combination of a cage having a vertical doorway and a top having a horizontal opening in direct unobstructed communication with said doorway, and horizontal door mechanism for normally guarding said top opening, said guard mechanism being pivoted intermediate of its ends below the plane of the cage top and comprising a plurality of independently movable sections.

In testimony whereof I affix my signature in presence of two witnesses.

JAMES W. BEACH.
